UNITED STATES PATENT OFFICE.

HERBERT J. SAUVAGE, OF CHICAGO, ILLINOIS, ASSIGNOR TO DRYING SYSTEMS, INC.,
OF CHICAGO, ILLINOIS, A CORPORATION OF ILLINOIS.

OIL BURNER.

Application filed October 25, 1926. Serial No. 143,966.

This invention relates to oil burners and the particular illustration shown in the drawings is useful for domestic heating purposes.

Heretofore it has been customary in this art, when rotating cups were employed for atomizing the liquid fuel, to drive these cups either with universal motors which are unreliable in certain respects, or to drive the cups at a speed corresponding to the normal speeds of induction motors when on standard circuits of sixty cycles. The atomization of the fuel is not efficient under these conditions, mainly due to the insufficient speed of rotation of the atomizing cup, and more efficient atomization was sought by enlarging the size of the rotating cup. When a universal motor is employed it gives considerable trouble, due to the use of a commutator and brushes, and also it is quite variable in speed, because of the differences in load and slight changes in voltage of the current driving it.

These and various other disadvantages heretofore encountered are overcome by my improved form of oil burner, and highly efficient atomization of the fuel oil is attained by rotating my small atomizer cup at a relatively high and uniform speed. This is accomplished by having my pump motor drive a high-frequency generator, preferably 180 cycles, the current from which in turn drives a two pole induction motor at approximately 10,300 R. P. M. The fuel atomizing cup is mounted on the shaft of this induction motor, and its extremely rapid rotation gives a very thorough and efficient atomization to the liquid fuel.

Further objects of this invention are to overcome certain operable limitations in the mechanical and electrical arrangements generally of fuel atomizing units; and to provide improved and simplified electrical controlling means for oil burners and fuel supply means, which will insure safe operation under widely differing conditions.

Another object accomplished by this invention is in the provision of means for automatically cutting off the current from the pump motor in case fuel is not supplied to the burner, or if supplied thereto, is not ignited, so that the heat from the products of combustion is not raised to a predetermined degree within a predetermined length of time.

A still further object of this invention is

to provide safety means for breaking the motor circuit in case the stack thermostat switch becomes blocked in one of its positions so that it can not return to its initial position upon the cooling of the stack.

An illustrative embodiment of this invention is shown in the accompanying drawings, in which

Fig. 1 is a view in perspective illustrating the general arrangement of a complete installation of oil burner and operating means therefor.

Fig. 2 is a diagram showing the electrically controlled means and the circuits therefor.

Fig. 3 is a vertical sectional view of the fuel atomizer induction motor and resilient means for mounting the motor.

Fig. 4 is a top plan view of the structure as shown in Fig. 3.

Fig. 5 is a sectional view taken on a line 5—5 of Fig. 3, showing a damper for controlling the flow of air through the burner.

Fig. 6 is a sectional detail taken on the line 6—6 of Fig. 3 with the motor housing removed, showing the three point suspension mounting of the motor unit.

Fig. 7 is a front elevation, partly in section, illustrating the arrangement of the motor and generator set and fuel pump driven thereby.

Fig. 8 is a vertical sectional view taken on the line 8—8 of Fig. 7.

Fig. 9 is a sectional view taken on the line 9—9 of Fig. 8.

Fig. 10 is a fragmentary view illustrating the valve arrangement of the pump.

Fig. 11 is a view in perspective illustrating one of the valves.

Fig. 12 is a section taken on the line of 12—12 of Fig. 15, with the parts in normal operating position.

Fig. 13 is a view of the same with the contacts open.

Fig. 14 is a view of the same with the parts being restored to their normal position.

Fig. 15 is an enlarged detail in elevation of a safety means for controlling the burner's circuit.

Referring to the drawings, Fig. 1 illustrates a househeating unit in which a furnace 1 is provided with the improved oil burner, the atomizing unit of which is indicated at 2. The motor 3 of this atomizing unit receives its current from a generator 4 driven by a

motor 5. The fuel pump also driven by the motor 5 is located within a housing indicated at 6 in Fig. 1. The housing 6 also serves as a fuel reservoir, as is illustrated, together with pump 7, in Figs. 7 to 11. The electrical controlling devices for the oil burner are mounted within a housing 8, Fig. 1.

The atomizer unit 2 illustrated in detail in Fig. 3, comprises a supporting frame 9 of U form, having adjustable supports 10, shown in Fig. 1, and carrying three adjustable posts 11, provided with springs 12, supporting centering pins 13 upon which rests the motor frame 14. This resilient mounting secures a very quiet operation of the atomizing unit, as the springs 12 absorb the vibrations of the motor, which otherwise would be transmitted to the floor of the furnace room. The frame 14 carries the field 15 of the motor and provides bearings 16 and 17 for the rotor shaft 18, the rotor being indicated at 19. A hood 14^a of inverted funnel shape is secured to the top of the motor frame 14 for keeping dust and dirt out of the motor. The rotor shaft 18, is housed between the bearings 16 and 17 for the purpose of carrying a lubricating oil from the oil container 20, upwardly to the bearing 17. This lubricating arrangement is specifically described and claimed in applicant's co-pending application for patent Serial No. 124,179, filed July 23, 1926.

The rotor shaft 18 carries a vertically disposed co-axial shaft in the form of a straight rod 21, which has a reduced portion 21' for imparting flexibility thereto, and is located adjacent the lower end of the rod 21, so as to utilize such flexibility for permitting the upper end of the shaft to secure a center of rotation under the gyrostatic effect of high speed. The shaft 21 supports an atomizing cup or revolving nozzle 22 on its upper end, a fan 23 is attached to the cup 22 for delivering a current of air which assists in atomizing the fuel. Additional air for supporting combustion passes upwardly around the atomizing unit through an air baffle 24. Fuel is supplied to the atomizer 22 by gravity from reservoir 37 in housing 6, through conduit 25, shut-off valve 25' and flow-regulating valve 25''. The conduit 25 is closed at its discharge or nozzle end except for a restricted orifice 26 at the side of the end of the conduit which faces the direction of rotation of the cup for directing fuel oil into the atomizing cup 22 in the direction of the rotation thereof. This arrangement of fuel discharge to the cup gives a very even and steady flame. The atomizing cup 22 is provided with a flange 27 of ring form surrounding a collar 28 at the lower end of the cup, and having its outer edge spaced slightly from the inner wall of the cup 22. The purpose of the flange 27 is to receive the fuel oil discharged from the aperture 26 and direct it by the shortest possible path to the inner wall of

the atomizer cup. The space 27' between the flange 27 and the bottom 29 of the cup is serviceable in collecting the few drops of excess fuel which could be delivered to the atomizer when coming to rest after an operation of the burner. The cup 22 is supported coaxially upon shaft 21 by a spider 30 secured to the shaft by the nut 31 clamping the spider between it and a collar 32. The spider 30 also supports through spacers 33, a cover plate 34 for the atomizer which is spaced from the upper edge of the atomizer only slightly to provide the annular outlet 35 for the fuel. This plate serves to prevent dust from settling into the cup and likewise it prevents any downward draft through the cup toward the fan 28 and the cup thus remains free from carbon deposit. The purpose of the baffle 24 is to separate and deflect the air uniformly outwardly in correspondence with the direction of the flame from the burner. Ignition is effected by means of a gas pilot burner indicated at 36 in Fig. 3. Regulation of the amount of air passing up through the atomizing unit is controlled by a damper which comprises a plate 24^a provided with openings 24^b, and a shutter 24^c, arranged to rotate relative to the plate 24^a. Shutter 24^c is provided with openings, disposed so as to register with the openings 24^b when in one position, and to be entirely out of registry when in another position. A variable amount of air is thus secured, depending upon the positioning of the shutter 24^c.

The fuel pump illustrated in Figs 7 to 11 serves to draw fuel from the supply tank upwardly into a fuel chamber reservoir 37, Fig. 7. The chamber 37 is provided with an over-flow connection 37^a back to the supply tank at the threaded aperture 38, therefore the chamber 37 only holds sufficient fuel to insure a fuel supply to the atomizer upon starting operations during the time that the pump becomes primed. The fuel flows from chamber 37 through the outlet 39 to conduit 25 shown in Fig. 3. The outlet 39 is normally closed by a valve 40 which is governor operated so that it is automatically opened only when the motor 5 has attained a predetermined speed. The shaft 41 of this motor carries at its right hand end Fig. 7, a centrifugal governor 42 arranged to rock to the right a bell crank lever 43 around its pivot 44 and an arm 45 of the bell-crank lever 43 engages beneath a collar 46 on valve 40. This action is effected against the action of a spring 47 for the valve. A horizontally extending arm 48 of the bell-crank lever is provided for the purpose of permitting manual operation of the valve under certain conditions, namely; for the purpose of filling chamber 37 when no fuel is available to operate the thermal switch in the combustion chamber. By this manual operation of bell-crank lever 43 the

valve 40 may be allowed to remain closed against the action of governor 42 while chamber 37 is being filled by the pump. The bell-crank lever 43 is operated in this manner by drawing upwardly on knurled knob 49 on the top end of a rod 50 which, at its lower end is provided with a collar 51 for engaging the outer end of arm 48. In such an operation of rod 50 the circuit through the motor 5 is closed independently of the stack switch 52, relay 80 and electrically heated thermostatic element 94, the rod 50 being provided with a contact element 53 mounted upon an insulating block 54, which 15 closes contacts 55 and 56 shown in Fig. 2.

The fuel pump is of ordinary construction, including a reciprocating piston 57 operated by a connecting rod 57^a journaled on an eccentric 58 rigid with a worm gear 59 20 journaled on a shaft 59^a and driven by a worm 60 on the motor shaft 41. The depending rim 7^a of the pump cylinder has an annular trough 7^b secured thereto for catching any fuel which might leak past the piston 57, and a drain pipe 7^c communicates with said trough for carrying any such leakage to the reservoir 37. The inlet and outlet ports for the cylinder of the pump are indicated in Figs. 7, 8, and 10. The fuel is 25 drawn from a storage supply tank to the pump through a conduit 61, Fig. 1, leading to a tubular strainer 62, Fig. 7, the conduit 61 being threaded in the aperture 63 in the head of the pump. From the interior of the 30 tubular screen 62 the fuel is drawn through an intake port 64 to the cylinder of the pump by the down stroke of piston 57. The port 64 is controlled by a disk valve 65 which closes the port upon the up stroke 35 of the piston. The fuel in leaving the cylinder, passes through an outlet port 66 similarly valve-controlled to a conduit 67 which serves to conduct the fuel to the reservoir 37, Fig. 7. The housing 6 for the fuel pump 40 is divided by a partition wall 68 separating the fuel reservoir 37 from chamber 69 which contains a lubricating oil for the pump, gears, and governor. Rapid rotation of the worm 60 throws lubricating oil 45 up an inclined wall 70^a, Fig. 8, into a trough 70, which conducts the oil to bearings 71 and 72, Fig. 7.

The electrical controlling means for the oil burner as diagrammatically illustrated 50 in Fig. 2, constitutes a supply line 73, provided with a time fuse 74 which functions to open the circuit in case the motor draws more than the normal current. A relay 75 for operating switch 76 for motor 5 is controlled by a room circuit A which includes 55 a pair of thermostatic switches 77 and 78, designated as a room thermostat and a boiler thermostat, respectively, and conductors 77^a, 77^b and 77^c. When these switches move to 60 closed position due to a drop in temperature, 65

to a predetermined point, the circuit A is closed and is energized, closing the switch 76 and permitting current to flow through conductor 79 to a relay winding 80 through normally closed switch 81, conductor 82 and thermal element 83, back to the line through conductors 84 and 85. The starting current of motor 5 is heavier than the normal running current thereof, and is sufficient to cause the relay 80 to rock switch arm 86 70 around its pivot 87 against the action of spring 88. Thus a pin 86^a on arm 86 momentarily moves away from spring contact member 89, permitting the member 89 to come in contact with a contact element 90. 75 The contact element 90 is connected by conductor 91 to a resistance element 92 which through a binding post 93 is connected to the return conductor 84. This provides a shunt circuit for bypassing part of the starting current around the thermal element coil 83, through the resistance element 92. Thus an abnormal amount of current is prevented from flowing through the thermal coil 83 which surrounds a bi-metallic thermostatic 80 element 94 and prevents a too rapid heating of the element. The thermostatic element 94 is a safety feature which serves to open the motor circuit in case the normal required amount of heat is not developed after a predetermined time upon the starting operation 85 of the burner. In case proper heat is developed within such time, a stack thermostatic switch 52, Fig. 2, rocks to a position where the contacts 95 are connected by the mercury 90 globule 96. Then part of the current normally flowing through the heating element 83 is shunted from conductor 79 through conductor 97, stack switch contacts 95 and back to the line through the conductors 98 and 85. 95 In case the stack switch fails to throw over as described, the thermostatic element 94, due to the heating thereof, rocks to the left, Fig. 2, permitting switch arm 99 to rock downwardly under the action of its spring 100, 100 opening the motor circuit at contacts 81. Manual means for restoring the contact at 81, comprises a lever 81^a, pivoted on the back wall of control box 8 in position to raise the arm 99 against the action of spring 100. The 105 outer end of the lever 81^a protrudes through a slot 81^b formed in the front wall of the control box, is shown in Figs. 1 and 12, and is preferably covered with insulating material. Lever 81^a carries a finger 81^c in 110 spaced and substantially parallel relation thereto and which is adapted to engage and bear down on the spring arm 99^a of arm 99 when the lever 81^a is raised to restore the connection and keeps the contacts at 81 separated until the lever is lowered to its normal position. Thus, if thermal element 94 is not in its normal position to support the arm 99, 115 the circuit to the motor is not closed by 120 movement of the lever 81^a. 125

In case the stack switch 52 becomes blocked in position so that contacts 95 remain closed after the stack has cooled, safety means are provided for rendering the system inoperative and comprises a circuit breaker 106 of the usual type, which is adapted to carry the normal running load of 3.3 amperes of the pump motor, but which will open the circuit through conductor 97 when the starting load 10 of 15 amperes for the pump motor passes therethrough.

It is desirable upon the starting operation of the burner, to create an artificial draft so that the normal operation of the burner may 15 be insured at such time, and also prevent any possibility of back pressure in the furnace resulting in products of combustion escaping in the wrong direction. For this purpose, the stack switch is normally in a position 20 where the contacts 101 are closed by the mercury. Therefore, when switch 76 is closed, the stack fan is set in operation and continues to operate until the stack switch throws over to position to closed contacts 95. 25 The return conductor 102 for the stack fan, leads back to the supply line in advance of the switch 76 and therefore, the operation of the stack fan does not effect the operation of the thermal element 83.

30 The circuit for the atomizer motor 3 is indicated on Fig. 2 by the numeral 103. These conductors connect the motor with the generator 4, the rotor of which is on shaft 41, and pass through the fuses 105, Fig. 2.

35 The operation of the device is brought out in general in the foregoing description. One of the most characteristic features of this burner is in the application of the motor generator set to an oil burner in order to 40 make possible the running of the induction motor for the atomizer at a higher speed than is possible on 60 cycles, for example, in the construction illustrated, the normal 60 cycles is stepped up to 180.

45 It is to be noted that the control system herein disclosed is particularly suitable for a motor in which the starting load is very high relative to its normal running load and this circumstance is a distinct advantage for 50 me, instead of being a disadvantage.

Although but one illustrative embodiment of this invention has been shown and described, many modifications may be had without departing from the spirit of the invention, as defined in the following claims.

I claim:

1. In a liquid fuel burner, the combination of a pump motor and a standard house power circuit therefor, a pump connected 60 with said motor, a generator driven by said motor for developing current of a frequency higher than that of said power circuit, an induction motor actuated by current from said generator, a rotative atomizing means directly connected to said induction motor,

and means for supplying fuel raised by said pump to said atomizing means.

2. In a liquid fuel burner, a pump motor circuit, a main switch for controlling said circuit, a room thermostat circuit, a relay in 70 said room circuit for actuating said main switch, a normally closed safety switch in said pump motor circuit, a thermal element controlled by the current in said pump circuit for opening said safety switch, a normally open stack circuit arranged, when closed, to divert the current from said thermal element, a thermostatic switch actuated by the heat of the products of combustion for closing said stack circuit, and a 80 circuit breaker in said stack circuit adapted to carry the normal running load of said pump motor and adapted to be opened by the starting load of said motor.

3. In a liquid fuel burner, a pump motor 85 circuit, a room thermostat circuit, means in said room circuit for controlling said pump circuit, a safety switch in said motor circuit, a thermal element controlled by the current in said motor circuit for normally holding 90 said safety switch in closed position, a normally open shunt circuit comprising a resistance element for by-passing current around said electric thermal element, and means actuated by the starting load of said pump 95 motor for closing said shunt circuit.

4. In a liquid fuel burner, the combination of a pump motor, a circuit including said motor, a fuel reservoir having a fuel outlet, a pump actuated by said motor for supplying fuel to said reservoir, an atomizer, means for supplying fuel from said reservoir to said atomizer, a valve normally closing said fuel outlet, automatic means for opening said valve when said pump motor has attained a predetermined speed, a safety switch normally closing said circuit comprising automatic electrical means operable by the current in said circuit for actuating said switch to open said circuit, and manually operated means for by-passing the current around said safety switch, said manually operated means coacting with said fuel outlet valve for inhibiting the opening of the latter when the circuit is bypassed around said safety 115 switch.

5. In a liquid fuel burner, the combination of a pump motor, a pump operatively connected with said motor, a generator driven by said motor, a burner motor actuated by 120 current from said generator, a rotative atomizing means directly connected with said burner motor, means for supplying fuel raised by said pump to said atomizing means, and thermostatic means for controlling operation of said pump motor.

Signed at Chicago this 21st day of October, 1926.

HERBERT J. SAUVAGE.
